(57) **CLAIM**

An ornamental design for a wallet, as shown and described.

DESCRIPTION

FIG. 1 is a top plan view of a wallet embodying my new design shown in a closed position;

FIG. 2 is a right side elevational view thereof;

FIG. 3 is a left side elevational view thereof;

FIG. 4 is a bottom plan view thereof;

FIG. 5 is a front elevational view thereof;

FIG. 6 is a rear elevational view thereof;

FIG. 7 is a first perspective view showing the front, the left side, and the top thereof;

FIG. 8 is a second perspective view showing the rear, the right side, and top thereof;

FIG. 9 is a third perspective view showing the rear, the left side, and the bottom thereof;

FIG. 10 is a fourth perspective view showing the front, the left side, and the bottom thereof;

FIG. 11 is a first perspective view showing the wallet of my design in a fully open position to reveal the interior;

FIG. 12 is a second perspective view showing the wallet of my design in a fully open position to reveal the interior; and,

FIG. 13 is a right side elevational view thereof.
